UNITED STATES PATENT OFFICE.

HOWARD S. FOLKER, OF SAN FRANCISCO, CALIFORNIA, ASSIGNOR TO NATIONAL SAFETY APPLIANCE COMPANY, OF SAN FRANCISCO, CALIFORNIA, A CORPORATION OF CALIFORNIA.

RAILWAY-TRAIN CONTROL.

1,322,418.

Specification of Letters Patent. Patented Nov. 18, 1919.

Application filed February 17, 1919. Serial No. 277,455.

To all whom it may concern:

Be it known that I, HOWARD S. FOLKER, a citizen of the United States, residing at the city and county of San Francisco and State of California, have invented certain new and useful Improvements in Railway-Train Control, of which the following is a specification.

This invention relates to improvements in train control mechanism adapted for use on railways and is an improvement on a construction illustrated in co-pending application Serial Number 259942, filed October 28, 1918.

One of the principal objects of the present invention is to provide an improved construction which is capable of assemblage in a small unit and is adapted for accurate operation to vent the train air pipe or operate other mechanism on the moving of the unit over a magnet or control mechanism. The device is capable of operation even when the vehicle is moving at extremely high speed and is but momentarily in contact with the control magnet or other operating means. A further object is to provide a construction composed of units which are capable of assemblage for venting the train air pipe or operating other mechanism, either on the forward or rearward movement of the train or vehicle, whereby a proper signal dependent on the position of the control magnet is transmitted to the vehicle.

The invention consists broadly in providing a polarized track magnet having a controlling keeper and positioned preferably at the entrance of a rail block and with which co-operate suitable auxiliary controlling valves and other control valves, the operation of which is controlled by the neutralizing of the magnetism of certain magnets which normally maintain said valves closed, the pole pieces of which are adapted for passing within the magnetic field of the permanent track magnet; all of said valves being capable of venting the train air line pressure, the train line pressure under certain conditions assisting to retain said control valves in their closed position.

With the above mentioned and other objects in view, the invention consists in the novel construction and combination of parts hereinafter described, illustrated in the ac-

companying drawings and pointed out in 55 the claims hereto appended; it being understood that various changes in the form, proportion, size and minor details of construction within the scope of the claims may be resorted to without departing from the 60 spirit or sacrificing any of the advantages of the invention.

To more fully comprehend the invention, reference is directed to the accompanying drawings, wherein—

Fig. 1 is a diagrammatic view of a track section at the entrance of a block, disclosing a track magnet and its controlling keeper, and the signal unit adapted to operate therewith.

Fig. 2 is a view in side elevation of an engine truck with the control unit carried thereby and in a position about to enter a block, as illustrated in Fig. 1.

Fig. 3 is a diagrammatic view of the 75 control unit illustrating the same connected to the train control air line.

Fig. 4 is a top plan view of one of the auxiliary control valves.

Fig. 5 is a top plan view of one of the 80 control valves.

Fig. 6 is a vertical sectional view taken on line 6—6 of Fig. 5.

Fig. 7 is a sectional view taken on line 7—7 of Fig. 4, viewed from the side of the 85 unit.

Fig. 8 is a sectional view taken on line 8—8 of Fig. 4, viewed from the end of the unit.

Fig. 9 is an enlarged sectional view of the 90 lower end of one of the control units illustrating more clearly the relief groove and relief channel.

Fig. 10 is an enlarged detail view of one 95 of the units.

Referring more particularly to the several views of the drawings, wherein like characters of reference designate corresponding parts, 1 indicates the supporting rails of a suitable railroad, the same being preferably 100 divided into blocks A and B by the insulations 2. At the entrance of each block, as illustrated in Fig. 1, there is positioned a polarized permanent track magnet 3, preferably of the horse-shoe type, and the keeper 105 4 of which is controlled by a suitable mechanism 5 operated in any suitable manner, as, for example, by the apparatus illustrated

in co-pending application Serial Number 223281.

As in Fig. 2 of the drawings, the truck 6 of a vehicle, preferably one of the tender 5 trucks of the engine, operating on the railway carries in spaced relation above the tracks a suitable apparatus 7 consisting of the independent units 8, 9, 10 and 11 secured to a supporting member 12 and arranged 10 thereon in a line parallel with the tracks 1, as in Figs. 1 and 2 of the drawings, the units 8 and 11, hereinafter termed auxiliary control units, are duplicates and are arranged at the opposite ends of the apparatus and 15 the units 9 and 10, hereinafter termed control units, are arranged toward the center of the apparatus, and are duplicates of each other. The units are connected by pipes, hereinafter described, with a suitable pipe 20 13 having positioned therein a cut-off valve 14, Figs. 2 and 3 of the drawings, and which valve is preferably located at a point on the locomotive which requires the engineer to dismount from the cab to the ground in 25 order to operate the same.

The control and auxiliary control units hereinafter described are identical in construction, with the exception that the control units, as illustrated in Figs. 3, 5 and 6, have 30 an air passage extending therein, which communicates with the bottom of the valve stem. It will be therefore apparent that a description of the construction illustrated in Fig. 8 will suffice for either the control or 35 auxiliary control units.

The units are constructed and the parts are arranged preferably in the following manner, reference being had to Figs. 4 to 8 inclusive of the drawings.

40 Each unit comprises a casing 15 having a removable head 16 adapted for attachment through the openings 17 to the underside of the support 12. The head 16 is provided in its center with a port 17 within the base 45 of which is received and held by a ring 18 a flexible valve disk 19, the opening 20 of which is adapted to be closed by the upper end of a vertically movable valve rod 21, the diameter of which is greater than the diameter 50 of the opening 20. The valve rod 21 in its movement controls the communication from the opening 17 through the port 20 to a vent channel 22 extending laterally through the head 16 and opening, as at 23, 55 to the atmosphere. The valve rod is normally maintained against the under-surface of the disk 19 to close the opening 20 by the magnetism of a suitable permanent magnet 24 mounted within the casing 15, and preferably of the horse-shoe type, said magnet attracting an armature 25 carried by the lower end of the valve rod 21. The opposite poles of said magnet extend laterally from the opposite sides of the casing 15, in the form 60 of arms 27, which carry on their extreme 65

ends the shoes or plates 28, these pole pieces being designed to pass within the magnetic field of the permanent track magnet 3 when the keeper 4 is released therefrom, whereby the magnetism of the unit magnet 24 is neutralized at such time as the pole pieces thereof enter the magnetic field of the track magnet 3 with said pole pieces of the unit magnet reversed to the poles of the track magnet.

75 The lower end of the valve rod 21 is guided in a chamber 29 and at the base of said valve rod is positioned a suitable valve plate or member 30 of a diameter less than that of the chamber 29, and against which 80 operates a spring 31 positioned within said chamber, which spring normally maintains the member 30 seated against the annular flange 30' which over-hangs the chamber 29. This construction provides a communication 85 between the chamber 29 and the upper surface of the member 30 when said member is released from its seat.

90 The tension of the spring 31 is sufficient to raise the valve rod 21 and its associated armature 25 to force the upper end of the valve rod in contact with the under-surface of the disk 19 when pressure in the opening 17 is cut off. When in this position the armature 25 co-operates with the magnet 24 maintaining the valve rod seated against the under-surface of the disk 19, and the magnet 24 is of sufficient strength to maintain the valve rod so seated against pressure in the pipe 13.

95 The pipe 13 communicates with a pipe 32 which at its opposite ends connects respectively with the opening 17 of the control valves 9 and 10, and from said pipe 32, intermediate of its connection with pipe 13 and the opening 17 of control valve 10, extends a suitable pipe 33 connecting with the opening 17 of the auxiliary control valve 8.

100 A similar pipe 34 connects with the pipe 32 intermediate its connection with the pipe 13 and the opening 17 of control valve 9 and communicates with the opening 17 of the auxiliary control valve 11. These pipes 32, 33 and 34 are preferably formed as bores or channels within the supporting member 12, but for purposes of clearness are illustrated in Fig. 3 as pipes.

110 The control valves 9 and 10, as heretofore stated, are similar in their construction to the auxiliary control valves 8 and 11; however the same differ in the following respects, reference being had to Figs. 5 and 6 of the drawings.

115 Extending vertically through the casing 15 of the units 9 and 10 is a relief channel 125 35, the lower end of which co-operates with the base of the chamber 29 below the disk 30 therein, as clearly illustrated in Fig. 3, and when the units are arranged, as in Fig. 2 of the drawings, the upper end of the 130

pipe 35 of the unit 9 intersects the pipe 34, and the upper end of the channel 35 of the unit 10 intersects the pipe 33.

In the respective pipes 33 and 34, intermediate 5 mediate the intersection of the channels 35 therewith and the point of connection of the respective pipes with the pipe 32, are positioned the choke fittings 36, as illustrated in Fig. 3 of the drawings.

10 The lower end of the valve rod of each of the control units 9 and 10 is provided with a safety leakage groove 37 which permits the venting of the air in chamber 29 of the control units to the interior of the 15 casing 15 of the respective units on the valves thereof being unseated.

In the device as assembled and arranged, particularly in Figs. 1 and 2 of the drawings, the units 8 and 10 control the venting 20 of the air line on the movement of the train in the direction of the arrow C while the units 11 and 9 control the venting of the air line on the backing of the train when the same is moving in the direction of the arrow 25 D, Fig. 1.

Referring particularly to Fig. 1 of the drawings, it will be observed that the poles of the magnets of the units 8 and 10 are arranged reversed to the poles of the permanent track magnet 3, while the poles of the units 11 and 9 are arranged to correspond with the poles of the permanent track magnet 3.

The train moving in the direction of the arrow C or D, in Fig. 1 of the drawings, with the keeper of the magnet connecting the poles thereof, no action will take place on the units passing over said magnet. However, on the disengagement of the keeper 4 from the poles of the magnet 3, due to the operation of the mechanism set forth in the previously mentioned co-pending application, a magnetic field is created above said poles of the magnet 3 and the movement 45 of the apparatus within the field thereof causes the operation of the units as follows. The valve 14 being opened, permits pressure to be built up in the pipe 13, which in turn, builds a pressure in pipes 32, 33, 34 and 35 through the choke fittings 36, which pressure is exerted against the upper 50 end of the stem 21 of each of the units 8, 9, 10 and 11. Pressure is also built up against the valve 30 at the lower end of the valve 55 stems 21 of the controlled valves 9 and 10.

In the forward engine movement in the direction of the arrow C, Fig. 1, the unit 8 enters the magnetic field of track magnet 3 first. Owing to the greater power of the track magnet 3 and the opposite arrangement of the poles of the magnet 24 of unit 8 thereto, the polarization of armature 25 of unit 8 is neutralized and the amature of said magnet associated with the valve rod is 60 released, permitting the air pressure in pipe

33 to force the valve rod of said unit downward against the tension of its spring 31. This movement of the valve rod 21 of the unit 8 provides a connection between pipe 33, through openings 17 and vent channels 70 22 and 23, venting the air pressure in pipe 32 and 33 to the atmosphere, also in pipe 35 associated with the control valve 10.

This operation of the auxiliary control unit 8 does not permit the venting of sufficient air from the pipe 13 to cause an application of the train's brakes as the choke fitting 36 in pipe 33 limits the escape of the air from pipe 32 through pipe 33 on the operation of the control unit 8. As the auxiliary control unit 8 passes from the magnetic field of the magnet 3, the armature 25 of said unit secured to the stem 21 of the valve rod thereof is raised by the spring 31 against the reduced air pressure in the 80 opening 17 to contact with the poles of the magnet 24 of said unit 8 by which it is energized and held, thus forcing the upper end of the stem into contact with the disk 19 shutting off the communication between 90 the end of pipe 33 and the atmosphere, permitting a pressure to be built up in the pipe 33 and pipe 35 extending therefrom. However, as the auxiliary control unit 8 is passing out of the magnetic field of the magnet 95 4 and before a pressure can be built up in the pipe 35 of the control unit 10, said control unit 10 is entering the field of the magnet 3, the movement of the control unit 10 into and through the field of the magnet 3 100 causes a neutralizing of the polarity of the magnet 24 of unit 10, which permits the pressure in pipe 32 to force the valve rod 21 of the unit 10 from its seat, which vents the air pressure in the end of pipe 32 associated with unit 10 to escape through the opening 17 in channels 22 and 23 of said unit 10 and as a precaution any pressure that is built up through the channels 35 and against the lower end of the valve rod 21 is released or 110 vented to the interior of the casing of unit 10 through the groove 37 at the lower end of the valve rod 21 of member 10; thus the air pressure in pipe 13 is vented to the atmosphere and said air pressure is of sufficient strength to maintain the armature 25 of the valve rod 21 of said unit 10 disengaged from its magnet 24 on the movement of the unit without the magnetic field of track magnet 4 and until such time as the 115 valve 14 is operated to cut off the pressure in the pipe 13 and, as heretofore explained, the operation of this valve requires the engineer to dismount from his cab, which assures the bringing of the vehicle to a stop 120 before the brakes can be released by the closing of the valve 14.

On the backing movement of the engine the auxiliary control unit 11 first passes through the field of the magnet 3 but it is 125 130

not operated thereby owing to the arrangement of the poles of the unit and the poles of the magnet. The control valve 1 next passes into the field of the magnet 3 and the power of said track magnet 3 neutralizes the magnet of said unit 10, but the air pressure in pipe 32 communicating with the unit 10 is unable to unseat the valve rod 21 as the pressure in the pipe 35 of the unit 10 is against the lower end of the valve rod 21 and thus the pressure on both ends of the valve rod are equalized. As the unit 10 passes without the field of the magnet 3 during the backing movement of the engine, the control valve unit 9 passes within the field of said magnet 3; the poles of the magnet of said unit are arranged similar to the poles of the magnet of the unit 11; said unit 9 is not operated but passes through the field of the magnet 3. The auxiliary control unit 8 then passes into and through the field of the magnet 3 and the power of said magnet 3 as previously described neutralizes the power of the magnet of this unit, but before the pressure in pipes 33 and branch pipe 35 communicating with unit 10 can be reduced sufficiently to permit the valve rod 21 of unit 10 to be forced from its seat, the armature of the magnet of the unit 8 is attracted by the magnet of the unit as the same has passed from the field of the track magnet 3 and the valve rod 21 of unit 8 is restored to normal closed position.

35 On the movement of the engine in the direction of the arrow D—Fig. 1 of the drawings, the magnet 3 controls the operation of the apparatus on the engine entering the block A and in this movement the auxiliary control unit 8 operates similarly to the operation of the control unit 11 in the backing movement, previously described, and the auxiliary control unit 10 similarly to the operation of the auxiliary control unit 9 in the backing movement, as previously described. In the backing movement of the engine as headed in the direction of the arrow D and within the block A the auxiliary control unit 11 operates similarly to the operation of the auxiliary control unit 8 in the forward movement, previously described, and the control unit 9 operates similarly to the operation of the control unit 10 in the forward movement, as previously described.

This four unit construction arranged in pairs provides an efficient control mechanism for a train air line adapted for the control operation of the vehicle when the unit carrying the same is headed in either direction on a given piece of track, either a double track where a permanent track magnet is positioned at the entrance to each block, or on a single stretch of track where the permanent track magnets are positioned

at opposite ends of each block with the poles of opposing magnets reversed, as in Fig. 2 of the drawings.

Having thus described my invention, what I claim as new and desire to protect by Letters Patent is:—

1. In combination with a railway vehicle having an air line opening to the atmosphere, said air line provided with a branch line having a restricted flow and also opening to the atmosphere, a valve unit and an auxiliary valve unit provided respectively with a valve and auxiliary valve closing against the pressure in said respective lines for controlling the openings of said respective lines to the atmosphere and arranged in spaced relation longitudinally of the vehicle, a relief valve directly connected with said valve unit and opening against the pressure in a relief channel extended from said lateral line to said valve unit, a polarized magnet associated with said valve and auxiliary valve for normally maintaining the same and said relief valve closed, said magnets arranged with corresponding poles toward the same side of said vehicle, a permanent polarized track magnet arranged with its poles reversed to the poles of said valve controlling magnets and within the field of which said valve magnets successively pass during the movement of the vehicle thereover, means associated with the said track magnet for controlling the magnetic field thereof, means for shutting off the pressure in said air line, and means for operating said valve members to closed position on the shutting off of the train air line flow.

2. In combination with a railway vehicle having an air line opening to the atmosphere, means for controlling the passage of air therethrough, a valve closing against pressure in said line for controlling the opening of said line to the atmosphere, a branch line extended from said air line and having a restricted flow and also opening to the atmosphere, an auxiliary valve closing against the pressure in said branch line for controlling the opening of the same to the atmosphere, a relief channel extended from said branch line and opening to the atmosphere, a relief valve directly connected with said valve and adapted for closing with the pressure in said relief channel, whereby the pressure against said relief valve approximately counterbalances the pressure against said valve, a polarized magnet associated with said valve and relief valve, a polarized magnet associated with said auxiliary valve and arranged with corresponding poles toward the same side of said vehicle, a polarized track magnet arranged with its poles reversed to the poles of said valve controlling magnets and through the field of which said valve magnets successively pass during

the movement of the vehicle thereover, and means for controlling the magnetic field of said track magnet.

3. A railway vehicle signal system including a controlling unit, a controlling valve therein, an air line having an escape to the atmosphere normally closed by said controlling valve, polarized magnetic means for normally maintaining said valve closed, an auxiliary controlling unit, an auxiliary controlling valve therein, a branch line of a restricted flow extending from said air line and having an escape to the atmosphere normally closed by said auxiliary valve, polarized magnetic means for maintaining said auxiliary valve normally closed, said means arranged with corresponding poles toward the same side of said vehicle, a connection extending from said branch line for maintaining a counterbalancing pressure against said controlling valve releasable on the operation of said auxiliary controlling valve, a polarized track magnet arranged with its poles reverse to the poles of said magnetic means and through the field of which said auxiliary controlling and controlling units successively pass during the movement of the vehicle thereover, and means for controlling the magnetic field of said track magnet.

4. A railway vehicle signal system including a controlling unit, a controlling valve therein, an air line having an escape to the atmosphere normally closed by said controlling valve, polarized magnetic means for normally maintaining said valve closed against the pressure in said air line, a restricted connection extending from said air line and communicating with said valve for maintaining a counterbalancing pressure against the same, magnetically operated means normally closed against the pressure in said restricted connection and capable of

operation to release said pressure, a polarized track magnet arranged with its poles 45 reversed to the poles of said magnetic means and said magnetically operated means and through the field of which said means are successively movable during the movement of the vehicle thereover, and means for controlling the magnetic field of said track magnet. 50

5. A valve unit for railway control systems including a body member provided with a connection leading to the vehicle air 55 line and opening to the atmosphere, said unit being further provided with a restricted connection also leading from the air line, a valve member within said unit and closing against the pressure in said first connection and opening against the pressure in said second connection, and a polarized magnetic means within said unit for maintaining said valve normally closed. 60

6. A valve unit for railway control systems including a body member provided with a connection leading to the vehicle air line and opening to the atmosphere, said unit being further provided with a restricted connection also leading to the air line and opening to the atmosphere, a valve member within said unit and closing against the pressure in said first connection and opening against the pressure in said latter connection, said valve when unseated permitting the pressure in both connections to escape to the atmosphere, and polarized magnetic means for maintaining said valve member seated. 65 70 75

In testimony whereof I have signed my name to this specification in the presence of 80 two subscribing witnesses.

HOWARD S. FOLKER.
